ATTORNEY

UNITED STATES PATENT OFFICE.

CHARLES ROBERTS, OF NEW YORK, N. Y.

SIGN MECHANISM.

Application filed January 18, 1923. Serial No. 613,347.

To all whom it may concern:

Be it known that I, CHARLES ROBERTS, a subject of the King of Great Britain, and a resident of the borough of Manhattan, city, 5 county, and State of New York, have invented certain new and useful Improvements in Sign Mechanism, of which the following is a specification, reference being had to the accompanying drawings.

10 An object of my invention is to provide a sign which will display in circuit successive reading matter or other characters.

Another object of my invention is to arrange the characters in rows and have each 15 row travel as a unit.

Another object of my invention is to provide magazines arranged in rows and said rows being arranged one above the other, each row of said magazines being adapted 20 to accommodate a plurality of characters in each of said magazines.

Another object of my invention is to provide means for continuously automatically effecting the succession of display of each 25 row of characters in its order.

Another object of my invention is to provide means for readily changing the matter to be displayed.

Other objects will be apparent upon the 30 reading of this specification in conjunction with the accompanying drawings, in which—

Fig. 1 is a cross section taken along the line 1—1 of Fig. 5 looking in the direction of the arrows;

35 Fig. 2 is a similar cross section with the operative parts in reversed position to that shown in Fig. 1;

Fig. 3 is a cross section taken along the line 3—3 of Fig. 1, looking in the direction 40 of the arrows;

Fig. 4 is a cross section taken along the line 4—4 of Fig. 1 looking in the direction of the arrows;

Fig. 5 is a cross section taken along the line 5—5 of Fig. 1 looking in the direction 45 of the arrows;

Fig. 6 is a cross section of a portion of the character raising mechanism;

Fig. 7 is a perspective view of one of the 50 characters used in my machine;

Fig. 8 is a cross section showing the carrier raising mechanism in modified form; and

Figs. 9 and 10 are similar views thereof

showing the same in different positions of 55 operation.

Referring now in detail to the drawings in which similar characters refer to similar parts throughout, 8 represents the frame of the machine and 9 the floor thereof. Mounted in said frame are the supports 10. In these supports is mounted the drive-shaft 11 having a drive-pulley 12 keyed thereon which is connected to any suitable source of power to give the said drive-shaft constant 60 revolving motion. On this drive-shaft are fixed the cranks 13 and 13^a which operate the links 14 and 14^a which links are connected at their other end to the sliding bar 15 adapted to slide in the slots 16 in the supports 10.

Mounted on the bar 15 are links 17 at the opposite end of which is pivoted the bar 18 which is adapted to slide in the recesses 19, 19^a through connecting pins 20 and 20^a in 70 the ends thereof. (See Fig. 5.) The bar 18 is normally held by the spring 21 mounted on the pin 22 in the link 17, against the pin 23 on the same link. Integrally connected with the said bar 18 are carriers 24 whose 75 most extended position projects them in the line of travel of the bottom block in the lower row of characters contained in the cartridges 25, but not far enough therein to interfere with the row of characters next to 80 the lowest row.

In one form of the embodiment of my invention shown there is mounted in the supports 10 another bar 26 which is adapted to oscillate therein and which is operated by 85 the link 27 keyed thereto at one end, the other end being in constant contact with the cam 28, said end being provided with suitable bearing means 29 for such purpose. Mounted on the said rod 26 are the suspension links 30, 30^a which support the bar 31. On this bar are mounted pressure projections 32. The link 30 is provided with a lug 50 which is normally held by the spring 33 to the pin 34 in the support 10 of the machine. (See Figs. 1, 2, 3, 5 and 6.)

In Figs. 8, 9 and 10, I have shown a modified form of mechanism for pressing the elevated block in position on the platform 36. In this form I eliminate the cam and link mechanism described in the previous paragraph. Mounted on the sliding rod 15 is the carrier 60 which extends across 100 105

the machine so as to be adapted to raise an entire row of characters, this carrier being provided with open slots 61 which are preferably located centrally of the respective blocks adapted to be raised by them. The sliding of this carrier is controlled by the link arms 62 and 63 which are hinged at 64. The arm 62 is loosely mounted on the bar 15 so as to oscillate thereon and the link 10 arm 63 is mounted on the power-shaft 11 so as to be operated thereby. The carrier 60 is made integrally with a trip 65 which moves therewith and which is preferably located in defense of the bottom of the slot 15 61. In the stationary guide 66 is pivotally mounted a dog 67, one leg of which is in the line of travel of the trip 65 and the other leg of which is adapted to press a character block which has been just raised 20 to its limit of height into place on the platform 36. A stop, which is in the form of a bar 68 passing through the various guides 66, is provided to limit the swinging of the dog 67 in both its arcuate directions. 25 Character blocks 35 are held in a plurality of rows in the magazines 25 on the platforms 36 and 37 respectively, such blocks being arranged in any suitable order such as for instance to form reading matter 30 which may readily be read through the opening 38 which may be covered with a transparent plate or covering 39, if desired. It will be understood in connection with the description of the embodiment of my 35 invention shown that there is a plurality of magazines and that the mechanism for raising character blocks which has just been described is duplicated with reference to each magazine, having connections, however, so that the operation upon the block in each magazine will be in unison with the operation on the blocks in the other magazines, all of the blocks in the bottom row of the lower chambers of the magazines being 40 raised at the same time and all of the blocks in the upper row of the upper chambers of the magazines being pushed off their common platform 36 at the same time. 45 The operation of the machine is as follows. The desired wording is arranged so as to form a row of reading matter before the opening 39, consisting of one character or one blank in each of the magazines 25 visible from said opening, and several rows consisting of several characters superimposed one on the other in each of said magazines, but which characters are so arranged so as to exhibit the desired reading matter when the superimposed characters 50 thereon have been removed. Each magazine is provided with the same number of characters as the other magazines in the machine and each stock of characters must correspond in number with those of the other magazines in the same machine. In 55

the case of continuous reading matter the characters on the blocks visible from the opening 39 are first read when said blocks fall out of their position as hereinafter described and the second row of characters is 70 then read and so on until all of the characters in the machine have performed a complete circuit of travel when the same matter will be exhibited and read in successive sections again. This operation will be continued as long as the machine is being driven. 75

Power is transmitted to the machine through the pulley 12 which is given a continuous movement. This pulley being on 80 the common shaft 11 with the cranks 13, 13^a which in turn are linked to the rod 15 carried in the guides 16, gives such rod a reciprocating movement in said guides. There being mounted on said rod the links 85 17 having the tilting carrier bar 18 at their lower ends to which is attached the carriers 24, one for each magazine, the said carriers will be raised and lowered carrying with them in their upward movement the row of characters lying at the back of the lower chambers of the magazines, one character in each magazine being raised at the same time. 90

Assuming the machine to be in the position shown in Fig. 1, the carrier 24 there being shown in its lowest position, the same will be raised until it assumes the position shown in Fig. 2, carrying with it one character in each magazine, which character is supported on its lateral edges by the flange 100 70 on the partition 71. This character will be held in the position shown in Fig. 2 until the cam 28 has operated on the roller 29 to oscillate forward the bar 26 on which is mounted the suspension links 30, 30^a carrying the rod 31 on which are mounted the pressure elements 32, one for each magazine, when pressure will be imparted to said pressure elements forcing the characters just raised onto the platform 36 and at the same time moving forward the entire stack of characters thereon and thereby pushing off the platform 36 the characters just exhibited, which fall by gravity onto the platform 37 and which on account of its inclined plane enables the characters just dropped to rest snugly against the stock of characters in the lower chambers of the magazines. The carriers 24 continuing in 110 their travel then move downward as shown in Fig. 6 and are tripped upward in their downward motion by contact with the lowest characters in the lower chambers of the magazines, such tripping being permitted 115 by the swivel mounting of the bar 18 to which the carriers are attached. As they continue downward in their travel they will 120 continue their tripped position until they reach the recesses 40 when they will again assume the position shown in Fig. 1 by 125 130

reason of the action of the spring 21 whose tension will draw bar 18 into such position, and to pin 23 which holds the said bar and carriers against further movement by the 5 said spring.

In the modified form shown in Figs. 8, 9 and 10, the carrier 60 is shown in its lowest position in Fig. 9, in its intermediate position in Fig. 8 and in its top position in 10 Fig. 10. The carrier is raised by means of the operation of the link mechanism 62 and 63 and connected at one end to the shaft 11 and adapted to travel therewith, and at the other end with the bar 15 and adapted to 15 swing thereon and reciprocating the same in the slot 16. In its upward movement the lowest row of character blocks in the lower chambers of the magazines are raised until the same are positioned slightly above the 20 platform 36, the strips 65 at the same time engaging the legs of the dogs 67, which are in its line of travel, and swings said dogs so that their opposite legs will be forced 25 against the character blocks, just raised putting it into their position as the lowest characters in the upper chambers at the same time pushing the top characters in said upper chambers off the platform 36, thereby 30 effecting their fall by gravity to the lower chambers.

The machine is now in position for another cycle of movement, raising the row of characters in the lowest position in the lower chambers of the magazines to the lowest 35 position in the upper chambers of the magazines, and pushing off the platform 36 the top row of characters thereof.

I have described what I believe to be the best embodiment of my invention. I do 40 not wish to be limited, however, in patent protection to the embodiment shown and described but what I desire to cover by Letters Patent is set forth in the appended claims.

45 Claims—

1. In sign mechanism, a plurality of magazines arranged in a row, a lower and upper chamber in each magazine, each of said chambers being adapted to contain a plurality of character blocks superimposed therein and resting on their lower edges, the floors of said chambers inclining inwardly, the floor of the upper chambers extending to a line to provide a space between 50 said floor and the back of said chambers, and means for raising the lowest row of character blocks in the lower chambers through said space to assume the position of the lowest row of character blocks in the upper chambers, and thereby discharge from said upper chambers the upper row of character blocks therein which descend by gravity to assume the position of the upper row of character blocks in the lower chambers.

60 2. In sign mechanism, a plurality of mag-

azines arranged in a row, a lower and upper chamber in each magazine, each of said chambers being adapted to contain a plurality of character blocks superimposed therein and resting on their lower edges, 70 the floors of said chambers inclining inwardly, the floor of the upper chambers commencing at a line within that of the commencing of the floor of the lower chambers and extending to a line toward the rear thereof within the line of the rear of the floor of the lower chamber so as to provide a space in the rear of the floor of the upper chambers, and means for raising the lowest row of character blocks in the lower 80 chambers through said space to assume the position of the lowest row of character blocks in the upper chambers, and thereby discharge from said upper chambers the upper row of character blocks therein which 85 descend by gravity to assume the position of the upper row of character blocks in the lower chambers.

3. In sign mechanism, a plurality of magazines arranged in a row, guides in the rear of said magazines adapted to control the direction of character blocks travelling thereon from the lower row of chambers to the upper row of chambers, each of said chambers being adapted to contain a plurality of character blocks superimposed therein and resting on their lower edges, the floors of said chambers inclining inwardly, the floor of the upper chambers commencing at a line within that of the commencing of the floor of the lower chambers and extending to a line to provide a space between said floor and the said guides, and means for raising the lowest row of character blocks in the lower chambers through said space to assume the position of the lowest row of character blocks in the upper chambers, and thereby discharge from said upper chambers the upper row of character blocks therein which descend by gravity to assume the position of the upper row of character blocks in the lower chambers.

4. In sign mechanism, a plurality of magazines arranged in a row, a lower and upper chamber in each magazine, guides located at the inner ends of said chambers and means for raising rows of character blocks along said guides from the lower chambers to the upper chambers, and thereby discharge from said upper chambers the upper row of character blocks therein which descend by gravity to assume the position of the upper row of character blocks in the lower chambers.

5. In sign mechanism, the method of successively displaying character blocks which consists of locating character blocks in two stacked rows successively raising the lowest row of character blocks in one stack to the position of the lowest row of character

blocks in the other stack, and in positioning said last raised row of character blocks in the upper stack, expelling the top row of character blocks from said upper stack and 5 by gravity positioning the said expelled row of character blocks in the lower stack on their lower edges.

6. In sign mechanism, lower and upper chambers in alignment with each other, said 10 chambers having inclined floors toward the rear thereof, the floor of the lower chamber extending beyond the lateral edges of the floor of the upper chamber, a common guide in the rear of each upper and lower 15 chamber and means for raising the row of character blocks adjacent said guides from the lower chambers, and along said guides to the upper chambers, and means for positioning said row of characters just raised 20 on the floor of the upper chambers, and thereby discharge from said upper chambers the upper row of character blocks therein which descend by gravity to assume the 25 position of the upper row of character blocks in the lower chambers.

7. In sign mechanism, lower and upper chambers in alignment with each other, said chambers having inclined floors toward the rear thereof, the floor of the lower chamber 30 extending beyond the lateral edges of the floor of the upper chamber, a common guide in the rear of each upper and lower chamber and means for raising the row of character 35 blocks adjacent said guides from the lower chambers, and along said guides to the upper chambers, swivelled lugs, a tripper movable with the aforesaid carrying mechanism, said tripper being adapted in its movement to turn said lugs on their swivel and thereby 40 cause said lugs to force said row of character blocks just raised into position on the floor of the upper chambers, and thereby discharge from said upper chambers the upper row of character blocks therein which 45 descend by gravity to assume the position of the upper row of character blocks in the lower chambers.

8. In sign mechanism, lower and upper chambers in alignment with each other, said 50 chambers having inclined floors toward the rear thereof, the floor of the lower chamber extending beyond the lateral edges of the floor of the upper chamber, a common guide in the rear of each upper and lower chamber 55 and means for raising the row of character blocks adjacent said guides from the lower chambers, and along said guides to the upper chambers, swivelled lugs, a tripper movable with the aforesaid carrying mechanism, said tripper being adapted in its movement to turn said lugs on their swivel and thereby cause said lugs to force said row of character blocks just raised into position on the floor of the upper chambers, and expel the 65 row of character blocks just displayed from

the upper chamber, which fall by gravity, assuming the position of the upper character blocks in the lower chambers.

9. In sign mechanism, lower and upper chambers having inclined floors toward the rear thereof, said chambers being in alignment with each other, the lateral edges of the floor of the upper chamber being within 70 the lateral edges of the floor of the lower chamber, stacks of character blocks in said chambers, guides located in the rear of said chambers to which the lowest rows of character blocks in said lower and upper chambers are adjacent, a carrier adapted to reciprocate along said guides and raise the 75 lowest row of character blocks in the lower chambers and deposit the same in the position of the lowest row of character blocks in the upper chambers, and thereby discharge from said upper chambers the upper 80 row of character blocks therein, which descend by gravity to assume the position of the upper row of character blocks in the lower chambers, and means for reciprocating 85 the aforesaid carrier. 90

10. In sign mechanism, a row of magazines having lower and upper chambers in line with each other, said chambers being adapted to contain stacks of character 95 blocks, guides in the rear of said chambers adapted to guide character blocks in their travel from the lower chambers to the upper chambers, said magazines being provided with communicating passages between said lower and upper chambers for that purpose, carriers adapted to reciprocate between the lower chambers and the upper chambers, and carrying with them in their upward travel character blocks lying adjacent to said guides and depositing the same 100 in said upper chambers, and thereby discharge from said upper chambers the upper row of character blocks therein which descend by gravity to assume the position of the upper row of character blocks in the 110 lower chambers, a wheel and link mechanism connected to the aforesaid carriers and adapted to reciprocate said carriers in line with a guide groove controlling the direction of travel of the same. 115

11. In sign mechanism, a magazine having upper and lower chambers, inclined floors in said chambers, the floor of the upper chamber being spaced from the rear thereof to permit character blocks to be passed by the rear end of said upper inclined floor, means for raising character blocks, a presser element adapted to press forward the character blocks in said upper chamber, and thereby discharge character blocks therefrom, said presser element being pivotally mounted adapted to operate in an arc, and stop for limiting the arcuate movement thereof, and means for positively operating said presser element. 120 125 130

12. In sign mechanism, a magazine having upper and lower chambers, inclined floors in said chambers, the floor of the upper chamber being spaced from the back of said magazine so as to permit character blocks to successively pass thereby, means for raising character blocks, a bifurcated presser element pivotally mounted and adapted to operate in an arc, and stop for

limiting the arcuate movement thereof, and 10 means for arcuately moving said presser element and thereby projecting one of the bifurcations thereof into presser contact with character blocks on the floor of said upper chamber, and thereby discharge character 15 blocks therefrom.

CHAS. ROBERTS.
